HERMAN F. D. CROWNFIELD, OF NEW YORK, ASSIGNOR TO M. H. BIRGE & SONS, OF BUFFALO, NEW YORK.

DESIGN FOR WALL-PAPER.

SPECIFICATION forming part of Design No. 23,650, dated September 25, 1894.

Application filed August 13, 1894. Serial No. 520,213. Term of patent 8½ years.

To all whom it may concern:

Be it known that I, HERMAN F. D. CROWNFIELD, a citizen of the United States, residing at New York, in the county and State of New York, have invented and produced a new and original Design for Wall-Paper, of which the following is a specification.

The design consists of a series of ornaments each composed of a center ornament of the Empire style, a laurel wreath with a flambeau-shaped ornament in the center of said wreath, and a flowing ribbon below said wreath, said ornaments being placed at uniform distances apart in vertical rows with festoons formed of small ornaments below each ornament and vertical stripes formed of a row of small ornaments and a center row of larger ornaments of the Empire style be-

tween each row of ornaments as represented in the accompanying drawing.

The border or upper portion of the design is formed of a series of ornaments of the Empire style and ornamental scrolls with an ornamental band at the top, and an ornamental band at the bottom with interlaced branches of laurel wreaths in the bottom band as shown in the drawing.

What I claim is—

The design for wall paper herein shown and described.

Witness my hand this 8th day of August, 1894.
